CLAIM

The ornamental design for a surgical tool, as shown and described.

DESCRIPTION

FIG. 1 is an isometric view of a surgical tool of the present invention.

FIG. 2 is a left side plan view of the surgical tool.

FIG. 3 is a right side plan view of the surgical tool.

FIG. 4 is a top plan view of the surgical tool.

FIG. 5 is a bottom plan view of the surgical tool.

FIG. 6 is a rear plan view of the surgical tool; and,

FIG. 7 is a front plan view of the surgical tool.

The broken lines shown in FIGS. 1-7 illustrate portions of the surgical tool that form no part of the claimed design.
